UNITED STATES PATENT OFFICE.

JOHN E. FREY, OF PITTSBURGH, PENNSYLVANIA.

FIRE-ESCAPE.

1,192,615.

Specification of Letters Patent. Patented July 25, 1916.

Application filed December 16, 1915. Serial No. 67,132.

To all whom it may concern:

Be it known that I, JOHN E. FREY, a citizen of the United States, residing at Pittsburgh, in the county of Allegheny and State 5 of Pennsylvania, have invented a new and useful Improvement in Fire-Escapes, of which the following is a full, clear, and exact description, reference being had to the accompanying drawings, forming part of 10 this specification, in which—

Figure 1 is a side elevation of one form of my improved fire escape, shown in position with relation to a building structure. Fig. 2 is a side elevation partially in section 15 of the escape shown in Fig. 1, on a larger scale; and Fig. 3 is a perspective view of the fire escape supporting sleeve.

This invention relates to an improvement in fire escapes of the suspension type, and 20 which may be used as a portable escape, or may be permanently secured in position on the building adjacent to a suitable exit.

The object of my invention is to provide a device of this character which can be readily 25 placed in position, which will be cheap and efficient; and in which the flexible suspension members are incased within telescopic sections down which the user can slide.

I am aware that there are a great many 30 portable fire escapes on the market, which consist mainly of a rope and suitable slings which are adapted to slide over the rope, but such devices are dangerous, as it is well known that the friction caused by sliding 35 over the rope will burn and cut the hands and legs of the person sliding over the same.

The precise nature of my invention will 40 be best understood by reference to the accompanying drawings, which will now be described, it being premised, however, that various changes may be made in the details 45 of construction and arrangement of the parts, without departing from the spirit and scope of my invention as defined in the appended claims.

Referring to the accompanying drawings the reference character 2 designates a wall 50 of a building, and 3 a window frame adjacent to which I have connected one form of my improved escape. This fire escape comprises a sliding pole which is built up of a plurality of telescopic sections 4, which are connected to each other by means of flexible

supporting members 5 within the sections. 55 In the drawings I have shown a plurality of such flexible supporting members, each of which is connected to clips 6 secured to adjacent sections, but if desired, a single flexible connecting member may be made to extend through the entire structure and connected to the various sections at different points, the arrangement being such that the sections can be pushed into each other, and the flexible supporting members will be 65 coiled up within the structure. Connected to the top of the upper section is a cap member 7 and extending through an opening in this cap member is a cord 8, which is connected to a pointed plug 9 seated in the lower 70 end of the bottom section, and is arranged to pull up the various sections into the upper section and retain them in such position by securing the cord to a cleat 10.

If desired the device may be secured 75 permanently to the building, but I prefer to provide a clamping member which is adapted to engage both sides of the wall below a window to retain the device in position, it being understood that the device is long 80 enough to reach the ground. The removable clamp comprises a jaw member 12 which is pivotally connected at one end to trunnions 13 on a sleeve 14 which is secured 85 to the upper section, and pivotally connected to this jaw member 12 is a second jaw member 15, which extends through the window and engages the inside of the wall. The member 12 is provided with a plurality of 90 openings, so that there is an adjustable connection between the members 12 and 15.

When the device is used as a portable fire escape the parts are pushed together and held in this position by means of the cord 8. The device is then passed out through the 95 window and the member 15 placed in the position shown in Fig. 1, and the weight on the member 12 will securely clamp the parts in a fixed position with relation to the wall. The cord 8 is then released, and the sectional 100 members allowed to fall, the point 9 will slightly embed itself in the ground or even in a concrete pavement to assist in steadyng the device, the pole is then in a position to be used as a sliding pole, the various sections being supported by the flexible members 5.

The advantages of my invention result

from the provisions of an extensible sliding pole, together with means for clamping it in position on the wall of a building.

I claim:

5. 1. A fire escape, comprising a sliding pole having a plurality of telescopic sections, flexible supporting members within said sections and connected thereto, in such a manner that all of the sections are adapted to be supported thereby, and a suspending member connected to the upper section and arranged to form a support for the device; substantially as described.
10. 2. A fire escape, comprising a sliding pole having a plurality of telescopic sections, flexible supporting members within said sections and connected thereto, in such a manner that all of the sections are adapted to be supported thereby, a suspending member connected to the upper section and arranged to form a support for the device, and a flexible member within the telescoping sections arranged to close the device; substantially as described.
15. 3. A fire escape, comprising a flexible member, means for securing the upper end to a building, and a metallic casing for said

flexible member formed of a plurality of telescopic members, each of said members being connected to the flexible member and arranged to be supported thereby; substantially as described.

4. A fire escape comprising a flexible member, means for connecting the upper end of the flexible member to a building, and a metallic casing for said flexible member formed of a plurality of telescopic members connected thereto and arranged to be supported thereby; substantially as described.

5. A fire escape, comprising a sliding pole having a plurality of telescopic sections, flexible supporting members within said sections and connected thereto, in such a manner that all of the sections are adapted to be supported thereby, and a clamping device connected to the upper section and arranged to form a support for the device; substantially as described.

In testimony whereof, I have hereunto set my hand December 11th A. D. 1915.

JOHN E. FREY.
